F. W. SCHOENEN.
SUBMARINE CONSTRUCTION FOR DIVING PURPOSES,
APPLICATION FILED SEPT. 30, 1916.

1,255,234.

Patented Feb. 5, 1918.

UNITED STATES PATENT OFFICE.

FREDERICK W. SCHOENEN, OF GREAT FALLS, MONTANA.

SUBMARINE CONSTRUCTION FOR DIVING PURPOSES.

1,255,234.

Specification of Letters Patent.

Patented Feb. 5, 1918.

Original application filed January 8, 1916, Serial No. 71,010. Divided and this application filed September 30, 1916. Serial No. 123,050.

To all whom it may concern:

Be it known that I, FREDERICK W. SCHOENEN, a citizen of the United States of America, residing at Great Falls, in the county of Cascade and State of Montana, have invented certain new and useful Improvements in Submarine Constructions for Diving Purposes, of which the following is a specification, reference being had therein 10 to the accompanying drawing.

This invention relates to a submarine construction for diving purposes, and covers certain subject-matter divided from my prior application relating to a submarine, 15 bearing Serial Number 71010.

The principal object of this invention is the production of a submarine, in which there are formed a number of rooms, which are adapted to alternately receive water, so 20 as to permit a diver to enter one room and leave the ship when desired, although upon his return the water from the diver's room may be emptied into a waste room, thus permitting the diver to enter the main body or 25 room of the submarine.

Another object of this invention is the production of a simple and efficient means for conveying the water from the diver's room to the waste room and afterward expelling the water from the waste room to the outer portions of the submarine.

With these and other objects in view, this invention consists of certain novel combinations, constructions, and arrangement of 35 parts, as will be hereinafter fully described and claimed.

In the accompanying drawing:

Figure 1 is a sectional view through the forward end of a submarine, illustrating the 40 construction of the diver's room and waste room.

Fig. 2 is a fragmentary sectional view, taken on the line 2-2 of Fig. 1, looking in the direction of the arrow.

Referring to the accompanying drawing by numerals it will be seen that the device 45 comprises a submarine shell, which, of course, may be of any desired construction and size. The main floor 2 extends longitudinally of the shell 1, and is supported by the partition 3, at a distance from the lower portions of the shell 1. A secondary flooring 4 is positioned within the shell 1, being spaced above the main floor 2, while this 55 secondary flooring is supported upon the

wall 5, engaging its inner end. A secondary wall 6 is positioned upon the secondary floor 4, and this wall 6 is provided with an opening 7. The cover 8 is pivotally mounted upon the wall 6, in any suitable manner, so 60 as to close the opening 7, when necessary. The forward end of the shell 1 is also provided with a manhole 9, which is normally closed by the trap door 10. This trap door 10 is pivotally supported in any suitable 65 manner, as shown at 11, and is normally retained in a closed position, by means of the set screw 12. This set screw 12 passes through the trap door 10, and into the body of the shell 1, as shown in Fig. 1, thereby re- 70 leasesably retaining the trap door 10 in a closed position.

When the diver desires to leave the submarine, he first enters the diver's room, indicated at 13, through the opening 7 formed 75 in the secondary wall 6. The cover 8 may then be swung to a closed position and locked in this manner, by any suitable means. The diver may then operate the valve 14 so as to permit the water to enter 80 the diver's room 13, while the air from this diver's room may pass into the waste room 15, through the valve 16 and pipe 17. It will be seen that this valve 16 is carried in the top of the diver's room, and therefore is 85 carried above the water level until the room is nearly filled. Just before the room is filled, however, it is necessary to cut off the valve 16, so as to prevent the passage of the water at this time into the waste room 15. 90 After the diver's room is filled, as above set forth, the set screw 12 may release the trap door 10, so as to permit the diver to pass through the manhole 9, thus leaving the submarine. After the diver has accomplished 95 his purpose, he may again return through the manhole, closing and locking the trap door, in the manner above set forth. At this time the valve 14 should be cut off, so as to prevent water upon the exterior of 100 the submarine from entering the same. The valve 18 carried by the elbow 19 may then be opened, while the valve 16 is also open. The water within the diver's room will then pass through the valve 18 and elbow 19, into 105 the waste room, while the air from the waste room will pass through the pipe 17 and valve 16 into the diver's room. After the diver's room has been emptied, the diver may then pass into the main portions of the sub- 110

marine, through the opening 7 in the secondary wall 6.

After the waste room 15 has received the water from the diver's room, it may be emptied by the pump 20, carried within the main portions of the submarine. A pipe 21, controlled by the valve 22, is connected to the pump 20, and extends into the waste room. Another pipe 23 communicates with 10 the pump 20 and with the exterior of the submarine shell 1 by extending through this shell, as shown at 24. It is, of course, obvious that this pump 20 is operated by means of the motor 25, or any suitable construction, 15 so that when the pump is in operation, water will be drawn from the waste room 15, and will be expelled through the pipe 23. Thus it will be seen that the waste room may be very easily emptied, so as to be in condition 20 to again receive water from the diver's room, when desired.

From the foregoing description it will be seen that a very simple and efficient construction has been provided for a submarine, 25 which will permit the ingress and egress of a diver, with respect to the diver's room, while the arrangements of the pipes will permit the diver's room to be filled with water or emptied when desired, while, in 30 turn, the pump and motor will empty the the waste room, when necessary.

What is claimed is:

1. In a submarine construction of the class described, the combination of a shell, a main 35 floor carried within said shell, a partition supporting said main floor, a second floor spaced above said main floor, a wall carried by said main floor and supporting the rear end of said second floor, a second wall engaging the inner portion of said shell and resting upon said second floor, whereby a 40 waste room is formed between said floors, and a diver's room is formed above said second floor, said second wall having an opening, means for closing said opening, said shell having an opening, means for closing said last-mentioned opening, said openings communicating with said diver's room, a pipe carried by said second floor, and extending to the upper portions of said diver's room, a valve carried by said pipe, a valve carried by said shell, whereby water may pass through said last-mentioned valve into said diver's room, at which time the air from the diver's room may pass through said first-mentioned valve and said pipe into said waste room, an elbow carried by said second floor, a valve carried by said elbow, whereby after said second-mentioned valve is closed, said last-mentioned valve may be opened, so as to permit the water within the diver's room to pass into the waste room, at which time the air within the waste room will pass through said pipe, and said first-mentioned valve, into said diver's room, a pump carried by said main floor, means for operating said pump, a pipe carried by said pump and communicating with said waste room, and a second pipe carried by said pump and communicating with the exterior of said shell, whereby said pump may draw the water from said waste room and expel same through said second-mentioned pipe upon the exterior of the submarine.

2. In a submarine construction of the class described, the combination of a shell, a main floor carried within said shell, a partition supporting said main floor, a second floor spaced above said main floor, a wall carried by said main floor and supporting the rear end of said second floor, a second wall engaging the inner portion of said shell and resting upon said second floor, whereby a waste room is formed between said floors, and a diver's room is formed above said second floor, said second wall having an opening, means for closing said opening, said shell having an opening, means for closing said last-mentioned opening, said openings communicating with said diver's room, a pipe carried by said second floor and extending to the upper portions of said diver's room, a valve carried by said pipe, a valve carried by said shell, whereby water may pass through said last-mentioned valve into said diver's room, at which time the air from the diver's room may pass through said pipe, and said first-mentioned valve, into said diver's room, a pump carried by said main floor, means for operating said pump, a pipe carried by said pump and communicating with said waste room, and a second pipe carried by said pump and communicating with the exterior of said shell, whereby said pump may draw the water from said waste room and expel same through said second-mentioned pipe upon the exterior of the submarine.

3. In a submarine construction of the class described the combination of an elongated shell, a waste room formed within said shell, a diver's room formed upon said waste room, means for admitting water into said diver's room, means for permitting a diver to pass from said diver's room, means for receiving air adjacent the top of said diver's room and passing the air into said waste room and whereby the air may be saved, means for passing the water from said diver's room into said waste room and means for exhausting the water from said waste room.

4. In a submarine construction of the class described, the combination of an elongated shell, a waste room formed adjacent one end of said shell, a diver's room formed upon

said waste room, means for permitting a diver to pass into and out of said diver's room, a pipe connecting with the interior of said waste room adjacent the top thereof and projecting to a point near the top of said diver's room, a valve carried by the upper end of said pipe, means for admitting water into said diver's room at which time said valve may be operated for permitting 10 air to pass from the upper portions of said

diver's room through said pipe into said waste room, whereby the air may be saved and means for admitting the water from said diver's room into said waste room at which time air will repass through said pipe 15 and said valve into the upper portions of said diver's room.

In testimony whereof I hereunto affix my signature.

FREDERICK W. SCHÖENEN.
